UNITED STATES PATENT OFFICE.

JACOB EMIL SCHMANDT, OF HARRINGTON, WASHINGTON.

BAG-SEWING MECHANISM.

1,351,134.

Specification of Letters Patent. Patented Aug. 31, 1920.

Application filed November 23, 1918. Serial No. 263,858.

To all whom it may concern:

Be it known that I, JACOB EMIL SCHMANDT, a citizen of the United States, residing at Harrington, in the county of Lincoln and State of Washington, have invented certain new and useful Improvements in Bag-Sewing Mechanism, of which the following is a specification.

This invention relates to an improved bag sewing mechanism, and has for its primary object to provide automatic means for sewing together the opposite sides of bags such as are commonly used as containers for grain, which is simple and compact in its arrangement and can be readily applied to a combined harvesting and threshing machine, whereby the grain is sacked as it is harvested in the field.

It is also a more particular object of my invention to provide in combination with a sack support, bodily shiftable sewing mechanism, said mechanism forming a chain stitch through the walls of the bag or sack at its mouth as it is moved in one direction relative to the sack.

It is another important object of my invention to provide simple and effective means for automatically clamping and holding the twine in the return movement of the sewing mechanism and severing the twine from its connection with the bag or sack.

It is likewise an object of my invention to provide improved means for clamping together the opposed walls of the bag or sack at the mouth thereof and to support the bag in proper position relative to the movable sewing mechanism.

A further detail object of the invention is to provide means which will operate to prevent the possibility of breakage of the sewing needle in the return movement of the mechanism to its normal position.

With the above and other objects in view, the invention consists in the improved construction, combination and relative arrangement of the several parts as will be hereinafter more fully described, subsequently claimed and illustrated in the accompanying drawings in which similar reference characters designate corresponding parts throughout the several views, and wherein:

Figure 1 is a front elevation illustrating the preferred embodiment of my improved sewing mechanism;

Fig. 2 is an end view thereof;

Fig. 3 is a top plan view, the clamping means for the bag being shown in extended position in full lines and in its effective clamping position in dotted lines;

60

Fig. 4 is an enlarged side elevation of the bag clamp;

Fig. 5 is a top plan view of the clamp;

Fig. 6 is a section taken on the line 6—6 of Fig. 5;

65

Fig. 7 is a plan view showing the clamping jaws open to receive the side portions of the bag;

Fig. 8 is a section taken on the line 8—8 of Fig. 7;

70

Fig. 9 is a plan view showing the collapsible bag clamp with the sections thereof arranged in position to hold the mouth of the bag open;

Fig. 10 is a plan view illustrating the sewing mechanism, the top of the case or cover being removed;

75

Figs. 11, 12, 13, and 14 are detail views illustrating the several steps in the operation of the stitch forming mechanism;

80

Fig. 15 is a detail elevation of the needle;

Fig. 16 illustrates side and edge views of the looper member;

Fig. 17 illustrates side and edge views of the loop holding element;

85

Fig. 18 is a detail plan view of the means for tensioning and holding the twine;

Fig. 19 is a fragmentary plan view illustrating the relative arrangement of the parts in the return movement of the sewing mechanism and the manner in which the twine is cut;

Fig. 20 is an edge view of one section of the case illustrating the cutting knife;

Fig. 21 is an enlarged detail section taken on the line 21—21 of Fig. 19;

Fig. 22 is an enlarged vertical section illustrating the operating gearing for the sewing mechanism;

Fig. 23 is a section taken on the line 23—23 of Fig. 22;

Fig. 24 is a longitudinal section through a grain discharge spout illustrating an improved means for cutting off the feed when the sack or bag has been filled and showing the spout open; and

Fig. 25 is a similar view, the spout being closed.

Referring in detail to the drawings, 5 designates two similar frame members 110 which may be mounted or secured in any suitable manner upon the discharge end of

the threshing machine. As herein illustrated, these frame members are of channel bar construction and have lower, horizontally disposed rails 6 and upper, obliquely inclined rails 7. To these frame members, at one of their ends, the horizontally disposed angle bar 8 is secured by means of the bracket plates, indicated at 9. The angle bar 8 extends beneath the lower horizontal rails 6 of the frame members. Between said frame members, track bars 10 are arranged and fixed at one of their ends to the horizontal flange of the angle bar 8, the other ends of said track bars being connected by means of a bar 11. Slide bars 12 are movable upon the bars 10 and are connected at one of their ends by the transverse bar 13. To the other end of each of the bars 12, a depending bracket plate 14 is fixed, to which the vertical flange of an angle bar 15 is secured. A transverse shaft 16 is mounted in suitable bearings on the frame members 5, and a pair of spaced links 17 are rigidly fixed at one of their ends to the rod or shaft 16 adjacent the opposite ends thereof. The other ends of each pair of links are connected to a rod 18 which is pivotally connected to one of the slide bars 12, as shown at 19, at a point in spaced relation to the angle bar 15.

A shaft 16 is provided at one end with an operating crank 20 and by turning this crank through an arc of 180° , the bars 12 will be moved longitudinally on the track bars 10 through the medium of the rods 18 to move the angle bar 15 toward the angle bar 8. Each of the rods 18 is bowed intermediate of its ends, as shown at 21, to accommodate the horizontal shaft 16 in the latter position of the angle bar 15. The edges of the bag or sack, which is adapted to be clamped and held closed at its mouth by the movable angle bar 15, are held in a collapsible clamping or gripping device, which I shall now proceed to describe in detail.

Referring to Figs. 4 to 9 inclusive of the drawings, it will be seen that the sack supporting or gripping device includes a pair of longitudinal side plates 22 which are hingedly connected at their ends, as at 23, to end plates 24. The plates 24 at corresponding ends of the side plates 22, are hingedly connected to each other, as at 25. Each of these plates is formed along its lower longitudinal edge with teeth 26. Outer longitudinal side plates 27 are hingedly connected to the upper edges of the inner plates 22, as at 28, and to these outer side plates, the outer end plates 30 are hinged, as indicated at 29, said plates 30 being hinged to the corresponding inner end plates 24, as at 31. The inner ends of the outer plates 30 are spaced from each other, as clearly seen in Fig. 9. The outer side

plates 27 are each provided with flanges 32 projecting outwardly from its upper edge in spaced relation to the opposite ends of the plate. These plates 27 are also centrally formed with the upwardly projecting, outwardly inclined wings 33, to which handle rods 34 are riveted at their extremities. The plates 27 at the juncture of the wings 33 therewith, are connected to the inner side plates 28 by means of the spring hinges 35. The inner plates 22 are also centrally formed with upwardly projecting wings or flanges 36 in opposed relation to the wings 33. The outer plates 27 and 30 are provided upon their lower edges with spaced teeth, as shown at 37, which are alternately disposed with relation to the teeth 26 on the inner plates and project toward the same.

In the use of the sack gripping device, the upper edges of the sack are adapted to be engaged between the inner and outer series of plates, the handles 34 being forced toward each other so that the outer series of plates are moved outwardly into angular spaced relation to the inner plates, as shown in Fig. 8. The handle members are then released so that the spring hinges 35 force the outer series of plates inwardly to their normal positions. Thus, the teeth 26 and 37 on the lower edges of the two series of plates engaging in the opposite sides of the walls of the sack will securely grip and hold the same. The sack is then disposed in position between the angle bars 8 and 15 with the flanges 32 resting upon the upstanding flanges of said bars. Thus, the mouth of the sack is held in a wide open position while the grain or other material is fed into the same. After the sack has been filled, the crank 20 is actuated as above explained. The outer angle bar 15 is thus moved inwardly and the pressure of the same against the sack gripping and supporting device, collapses said device, the ends thereof folding inwardly toward each other, as seen in Fig. 5, until the mouth of the sack is securely closed. The opposed walls of the sack are now stitched or sewed together at a point immediately below the clamping or gripping device, and for this purpose I have herein illustrated a sewing mechanism, which I have found to be very reliable and efficient in practical use. This mechanism in its preferred embodiment is constructed and arranged as follows:

To the vertical flange of the angle bar 8, at one side of the bag clamping means, a rack bar 38 is fixed and to the outer side of said rack bar, the angle bar 39 is secured. 40 designates a housing or casing within which the sewing mechanism is contained. This casing is disposed in a horizontal plane beneath the angle bars 8 and 39 and is provided at one of its ends with the spaced, peripherally grooved rollers 41 which travel

upon the horizontal flanges of the respective angle bars. 42 designates a housing which is secured to the upper side of the case 40 adjacent its opposite end and within 5 which the operating gearing for the sewing mechanism, to be later described, is mounted. Upon the opposite sides of this housing, adjustable bracket members 43 are arranged and carry the rollers 44 which are 10 engaged against the horizontal flange of the angle bar 39. The case 40 is formed with a slot 45 centrally thereof which extends longitudinally from one end of said casing to a point in spaced relation to its opposite end. 15 Within this slot, the upper end of the bag or sack is adapted to be received.

Upon a shaft 46, journaled in the housing 42, a spur-gear 47 is loosely mounted and is engaged with the teeth of the longitudinally extending rack bar 38. At each side of the gear 47, a beveled gear 48 is also loosely mounted upon said shaft. Each of these beveled gears is formed with a rectangular hub portion 49 to receive a ratchet wheel 50. Pawls 51 are pivotally mounted upon the opposite side faces of the gear 47, said pawls facing in the same direction and being engaged with the teeth of the respective ratchets 50. The pawls 51 are yieldingly held in engagement with the respective ratchets by means of the springs 52 which are preferably formed of wire and have their medial portions disposed through the gear 47, the terminals of each spring 25 having operative engagement with the corresponding pawls on opposite faces of the gear.

Fixed shafts 53, extending at right angles to the shaft 46, are also mounted in the 40 housing 42 and extend through the casing 40. Upon these shafts, a sleeve 54 is loosely engaged. A beveled pinion 55 is fixed to one end of each sleeve and meshes with the respective beveled gears 48. To the other 45 ends of the sleeves 54 and disposed within the casing 40, gears 56 are secured, said gears having meshing engagement with each other. It will, of course, be understood that the under side of the gear housing 42 is suitably formed or recessed to accommodate the angle bars 8 and 39 and the rack bar 38.

Upon a stub shaft 57 fixed to the body 55 wall of the case 40, a pinion 58 is loosely mounted, said pinion having meshing engagement with one of the gears 56. To one side of the pinion, a circular disk or plate 59 is fixed. In this plate adjacent its outer edge, a pin 60 is secured and has operative 60 engagement in a longitudinal slot 62 formed in one end of a needle actuating lever 61 which is fulcrumed intermediate of its ends upon the wall of the case, as at 63.

Upon the other end of said lever, a bracket 65 member 64 is pivoted, as at 65, and in said

member the shank of the needle 66 is adjustably secured by means of a suitable set screw 67. The bracket member is formed with an angularly projecting arm 68. To the end of this arm, one end of a contractile 70 spring 69 is attached, the other end of said spring being suitably connected to the lever 61. A slot 70 is formed in the vertical flange or wall of the case along one edge of the slot 45 therein and through the slot 70, 75 the point of the needle is adapted to be projected. In opposite ends of this slot, rollers 71 are mounted. Adjacent to the eye of the needle, indicated at 72, the needle shank is cut away or recessed on one side thereof, 80 as at 73, for a purpose which will be later explained.

Upon one of the frame members 5, a suitable box or receptacle 74 to receive the twine ball is mounted, and the marginal flange of the case 40 is formed with an eye or opening 75, through which the twine is extended. 76 designates a spring metal plate extending longitudinally within the case and having one of its ends fixed to the 90 marginal wall of the case by the screw 77. A second screw 78 is adjustable in the case wall and is engaged with said spring plate to regulate the tension thereof. The other end of this spring plate is formed with an 95 open guide eye 79 for the twine. From this eye, the twine is angularly extended and engaged through a guide 80 fixed to the case wall. From the latter guide, the twine extends to the guide button or head 81 mounted upon the wall of the case and is engaged in the curved slot or channel 82 formed in said head. From this guide head, the twine is extended through the eye of the needle. 100

Between the fulcrum of the lever 61 and the needle 66, a disk 83 is rotatably mounted upon a stub shaft 84 fixed in the case wall and is provided in its perimeter with a series of teeth 85 adapted to project through a slot or opening in the vertical flange along 110 one edge of the slot 45. A pin 87 is fixed in said disk adjacent its outer edge and has operative engagement in a slot 89 formed in the lever 88 which is fulcrumed intermediate of its ends, as at 90, upon the 115 case wall. To the other end of this lever, a link member 91 is pivotally connected, said link member being pivoted at its other end to the end of a rod 92 which is longitudinally movable in a suitable guide 93 fixed 120 within the case. The other end of the rod 92 is angularly off-set and a plate 94 is secured thereon, said plate extending longitudinally between the face of the end portion of the tensioning plate 76 for the twine 125 and the marginal wall of the case. This plate 94 is provided with a notch or recess 95 in its end to receive the twine when said plate is projected in one direction through the medium of the operating connections 130

with the disk 83. This disk is also formed in its edge with an angularly projecting lug 96, which, in the movement of the sewing mechanism in one direction, is adapted to engage the lever 61 and rock the same and move the needle 66 to a position entirely within the case.

In the case 40 and at the opposite side of the slot 45, additional pinions 97 and 98 respectively are journaled upon the stub shafts 99 and 100. Both of these pinions have meshing engagement with the other of the gear wheels 56, and to said pinions, the disks 101 and 102 are respectively fixed.

15 In a suitable guide 103 fixed to the wall of the case, a longitudinally reciprocating looper rod 104 is mounted, said looper rod having a laterally projecting, curved finger 105 formed on one edge thereof and being 20 also formed with a recess 106 extending longitudinally and inwardly from said finger. 107 designates a loop holding member which is pivoted, as at 108, and is formed with an off-set at one of its ends which is bifurcated, 25 as shown at 109, and is also provided with an angularly projecting finger or hook 110. 111 designates a guide plate secured in the case, with one end of which the looper rod 104 is engaged. The other end of said plate 30 is engaged with a second rod 112. One end of this rod is connected to the corresponding end of the looper rod 104 by a plate 113. It will be understood that the rod 112 and the guide plate 111 effectually prevent rotation of the looper rod and angular displacement of the finger 105. The plate 113 is operatively connected by means of a rod 114 to a wrist pin fixed in the disk 97. The member 107 is provided with an angularly 35 disposed arm 115 which is operatively connected in a similar manner to the other of the disks 102 by means of a rod 116.

The upstanding flange along the edge of the slot 45 adjacent to the end of the looper rod 104, whereon the hook 105 is provided, is formed with the slot 117 which is opposed to the slot 70 on the vertical flange along the other edge of the slot 45, and through which the twine is carried by the needle 66. At one end of this slot, a blade 118 is fixed to the inner face of the flange and has an obliquely disposed cutting edge 119.

The gear housing 42 carries a stud bolt 55 120, upon which an operating lever 121 is fulcrumed intermediate of its ends. A horizontally disposed bar 122 is secured to the angle bars 8 and 39 and an obliquely disposed brace bar 123 is fixed to the other end 60 of the bar 122 and to one of the frame members 5, said brace bar having its medial portion bowed or angularly off-set, as at 124. A U-shaped bar 125 is disposed in spaced relation to the central portion of said off-set and is fixed at its extremities thereto.

The operating lever 121 extends between the bowed portion 124 of the bar 123 and the bar 125, thus providing a guide for said operating lever. A movable link bar 126 connects one end of the operating lever to 70 the horizontal bar 122.

Assuming that the bag has been filled with the grain or other material and the bar 15 actuated to collapse the bag gripping means and tightly close the mouth of the 75 bag, the operator now grasps the end of the lever 121 and shifts said lever to the left. The case 40 carrying the sewing mechanism and the operating gearing therefor is thus caused to travel horizontally along the angle 80 bars 8 and 39 and in such movement, the gear 47 meshing with the teeth of the rack bar 38, effects the positive rotation of the gears 56. At the start of this movement, the teeth on the edge of the disk 83 engaging 85 with one side of the sack or bag, causes a rotation of said disk in the direction indicated by the arrow in Fig. 18, so that the plate 94 is shifted by the actuation of the lever 88 to the position seen in dotted lines 90 in said figure and out of engagement with the twine, so that the twine may be freely pulled or drawn through the opening in the marginal wall of the case 40 in the operation of the sewing needle. The opposed 95 walls of the bag or sack are sewed together by means of a chain stitch which is formed by the sewing mechanism in the movement of said mechanism relative to the bag in the following manner.

Reference may now be had to Figs. 11, 12, 13, and 14 of the drawings, wherein I have illustrated the several steps in the formation of the stitch. In the rotation of the disk 59, the lever 61 is actuated and the needle 66 carrying the twine is projected through the openings 70 and 117. As shown in Fig. 11, the needle has carried the twine through the sack walls. In such movement, the looper rod 104 is projected toward the needle and at the start of the return movement of the needle, the hook 105 on said rod engages the twine at one side of the needle. The needle point operates through the recess 106 in the side of the looper rod and by reason of its 115 pivotal mounting on the end of the lever 61, may swing laterally in said slot and between the rollers 71 due to the pressure of the sack walls against the needle shank. As the needle is withdrawn from the walls of 120 the sack, the movement of the rod 104 continues and the loop is formed in the twine at the front side of the sack or bag. During this operation, the loop holding element 107 is being actuated, and the curved hook 125 or finger 110 is engaged in the loop before the movement of the rod 104 is reversed, as shown in Fig. 12. In the next operation of the needle, the twine is again carried through the sack walls and between the op- 130

upon the horizontal flanges of the respective angle bars. 42 designates a housing which is secured to the upper side of the case 40 adjacent its opposite end and within 5 which the operating gearing for the sewing mechanism, to be later described, is mounted. Upon the opposite sides of this housing, adjustable bracket members 43 are arranged and carry the rollers 44 which are 10 engaged against the horizontal flange of the angle bar 39. The case 40 is formed with a slot 45 centrally thereof which extends longitudinally from one end of said casing to a point in spaced relation to its opposite end. 15 Within this slot, the upper end of the bag or sack is adapted to be received.

Upon a shaft 46, journaled in the housing 42, a spur-gear 47 is loosely mounted and is engaged with the teeth of the longitudinal 20 extending rack bar 38. At each side of the gear 47, a beveled gear 48 is also loosely mounted upon said shaft. Each of these beveled gears is formed with a rectangular hub portion 49 to receive a ratchet wheel 50. Pawls 51 are pivotally mounted upon the opposite side faces of the gear 47, said pawls facing in the same direction and being engaged with the teeth of the respective ratchets 50. The pawls 51 are yieldingly held in engagement with the respective ratchets by means of the springs 52 which are preferably formed of wire and have their medial portions disposed through the gear 47, the terminals of each spring 25 having operative engagement with the corresponding pawls on opposite faces of the gear.

Fixed shafts 53, extending at right angles to the shaft 46, are also mounted in the housing 42 and extend through the casing 40. Upon these shafts, a sleeve 54 is loosely engaged. A beveled pinion 55 is fixed to one end of each sleeve and meshes with the respective beveled gears 48. To the other 30 ends of the sleeves 54 and disposed within the casing 40, gears 56 are secured, said gears having meshing engagement with each other. It will, of course, be understood that the under side of the gear housing 42 is suitably formed or recessed to accommodate the angle bars 8 and 39 and the rack bar 38.

Upon a stub shaft 57 fixed to the body wall of the case 40, a pinion 58 is loosely mounted, said pinion having meshing engagement with one of the gears 56. To one side of the pinion, a circular disk or plate 59 is fixed. In this plate adjacent its outer edge, a pin 60 is secured and has operative engagement in a longitudinal slot 62 formed in one end of a needle actuating lever 61 which is fulcrumed intermediate of its ends upon the wall of the case, as at 63. Upon the other end of said lever, a bracket 65 member 64 is pivoted, as at 65, and in said

member the shank of the needle 66 is adjustably secured by means of a suitable set screw 67. The bracket member is formed with an angularly projecting arm 68. To the end of this arm, one end of a contractile 70 spring 69 is attached, the other end of said spring being suitably connected to the lever 61. A slot 70 is formed in the vertical flange or wall of the case along one edge of the slot 45 therein and through the slot 70, 75 the point of the needle is adapted to be projected. In opposite ends of this slot, rollers 71 are mounted. Adjacent to the eye of the needle, indicated at 72, the needle shank is cut away or recessed on one side thereof, 80 as at 73, for a purpose which will be later explained.

Upon one of the frame members 5, a suitable box or receptacle 74 to receive the twine ball is mounted, and the marginal flange of the case 40 is formed with an eye or opening 75, through which the twine is extended. 76 designates a spring metal plate extending longitudinally within the case and having one of its ends fixed to the 90 marginal wall of the case by the screw 77. A second screw 78 is adjustable in the case wall and is engaged with said spring plate to regulate the tension thereof. The other end of this spring plate is formed with an 95 open guide eye 79 for the twine. From this eye, the twine is angularly extended and engaged through a guide 80 fixed to the case wall. From the latter guide, the twine extends to the guide button or head 81 mounted upon the wall of the case and is engaged in the curved slot or channel 82 formed in said head. From this guide head, the twine is extended through the eye of the needle. 100

Between the fulcrum of the lever 61 and the needle 66, a disk 83 is rotatably mounted upon a stub shaft 84 fixed in the case wall and is provided in its perimeter with a series of teeth 85 adapted to project through a slot or opening in the vertical flange along 110 one edge of the slot 45. A pin 87 is fixed in said disk adjacent its outer edge and has operative engagement in a slot 89 formed in the lever 88 which is fulcrumed intermediate of its ends, as at 90, upon the 115 case wall. To the other end of this lever, a link member 91 is pivotally connected, said link member being pivoted at its other end to the end of a rod 92 which is longitudinally movable in a suitable guide 93 fixed 120 within the case. The other end of the rod 92 is angularly off-set and a plate 94 is secured thereon, said plate extending longitudinally between the face of the end portion of the tensioning plate 76 for the twine 125 and the marginal wall of the case. This plate 94 is provided with a notch or recess 95 in its end to receive the twine when said plate is projected in one direction through the medium of the operating connections 130

with the disk 83. This disk is also formed in its edge with an angularly projecting lug 96, which, in the movement of the sewing mechanism in one direction, is adapted to engage the lever 61 and rock the same and move the needle 66 to a position entirely within the case.

In the case 40 and at the opposite side of the slot 45, additional pinions 97 and 98 respectively are journaled upon the stub shafts 99 and 100. Both of these pinions have meshing engagement with the other of the gear wheels 56, and to said pinions, the disks 101 and 102 are respectively fixed.

15 In a suitable guide 103 fixed to the wall of the case, a longitudinally reciprocating looper rod 104 is mounted, said looper rod having a laterally projecting, curved finger 105 formed on one edge thereof and being 20 also formed with a recess 106 extending longitudinally and inwardly from said finger. 107 designates a loop holding member which is pivoted, as at 108, and is formed with an off-set at one of its ends which is bifurcated, 25 as shown at 109, and is also provided with an angularly projecting finger or hook 110. 111 designates a guide plate secured in the case, with one end of which the looper rod 104 is engaged. The other end of said plate 30 is engaged with a second rod 112. One end of this rod is connected to the corresponding end of the looper rod 104 by a plate 113. It will be understood that the rod 112 and the guide plate 111 effectually prevent rotation of the looper rod and angular displacement of the finger 105. The plate 113 is operatively connected by means of a rod 114 to a wrist pin fixed in the disk 97. The member 107 is provided with an angularly disposed arm 115 which is operatively connected in a similar manner to the other of the disks 102 by means of a rod 116.

35 The upstanding flange along the edge of the slot 45 adjacent to the end of the looper rod 104, whereon the hook 105 is provided, is formed with the slot 117 which is opposed to the slot 70 on the vertical flange along the other edge of the slot 45, and through which the twine is carried by the 40 needle 66. At one end of this slot, a blade 118 is fixed to the inner face of the flange and has an obliquely disposed cutting edge 119.

45 The gear housing 42 carries a stud bolt 120, upon which an operating lever 121 is fulcrumed intermediate of its ends. A horizontally disposed bar 122 is secured to the angle bars 8 and 39 and an obliquely disposed brace bar 123 is fixed to the other end 50 of the bar 122 and to one of the frame members 5, said brace bar having its medial portion bowed or angularly off-set, as at 124. A U-shaped bar 125 is disposed in spaced relation to the central portion of said off-set and is fixed at its extremities thereto.

The operating lever 121 extends between the bowed portion 124 of the bar 123 and the bar 125, thus providing a guide for said operating lever. A movable link bar 126 connects one end of the operating lever to 55 the horizontal bar 122.

Assuming that the bag has been filled with the grain or other material and the bar 15 actuated to collapse the bag gripping means and tightly close the mouth of the 75 bag, the operator now grasps the end of the lever 121 and shifts said lever to the left. The case 40 carrying the sewing mechanism and the operating gearing therefor is thus caused to travel horizontally along the angle 80 bars 8 and 39 and in such movement, the gear 47 meshing with the teeth of the rack bar 38, effects the positive rotation of the gears 56. At the start of this movement, the teeth on the edge of the disk 83 engaging 85 with one side of the sack or bag, causes a rotation of said disk in the direction indicated by the arrow in Fig. 18, so that the plate 94 is shifted by the actuation of the lever 88 to the position seen in dotted lines 90 in said figure and out of engagement with the twine, so that the twine may be freely pulled or drawn through the opening in the marginal wall of the case 40 in the operation of the sewing needle. The opposed 95 walls of the bag or sack are sewed together by means of a chain stitch which is formed by the sewing mechanism in the movement of said mechanism relative to the bag in the following manner.

100 Reference may now be had to Figs. 11, 12, 13, and 14 of the drawings, wherein I have illustrated the several steps in the formation of the stitch. In the rotation of the disk 59, the lever 61 is actuated and the needle 66 105 carrying the twine is projected through the openings 70 and 117. As shown in Fig. 11, the needle has carried the twine through the sack walls. In such movement, the looper rod 104 is projected toward the needle and 110 at the start of the return movement of the needle, the hook 105 on said rod engages the twine at one side of the needle. The needle point operates through the recess 106 in the side of the looper rod and by reason of its 115 pivotal mounting on the end of the lever 61, may swing laterally in said slot and between the rollers 71 due to the pressure of the sack walls against the needle shank. As the needle is withdrawn from the walls of 120 the sack, the movement of the rod 104 continues and the loop is formed in the twine at the front side of the sack or bag. During this operation, the loop holding element 125 is being actuated, and the curved hook or finger 110 is engaged in the loop before the movement of the rod 104 is reversed, as shown in Fig. 12. In the next operation of the needle, the twine is again carried through the sack walls and between the op- 130

posite sides of the loop held by the element 107, while the movement of the looper rod 104 is reversed. The needle point moves through the bifurcation 109 which serves as 5 a guide for the needle and insures the passage of the twine through the loop, in the manner shown in Fig. 13. After the needle point has entered this bifurcation, the movement of the member 107 is reversed and 10 the hook 110 thereof is withdrawn from the loop. In the continued movement of the sewing mechanism, the twine is, of course, carried across the end of the loop and in the reverse movement of the needle, the looper 15 member again is operatively engaged with the twine to form the next loop therein, as shown in Fig. 11. By providing the recess 73 in the side of the needle shank, the hook 105 on the looper rod may move therethrough 20 and properly engage the twine to form the loop. In this manner, the walls of the sack or bag may be quickly and securely sewed together and the mouth of the bag closed. At the end of the sewing operation, the operator 25 reverses the movement of the lever 121. The teeth on the disk 83 engaging one side of the sack, effect the rotation of said disk in a clockwise direction to move the plate 94 through the medium of lever 88 to the 30 full line position shown in Fig. 18 and engage the notched end 95 of said plate with the twine closely adjacent to the eye or opening 75 in the upstanding marginal wall of the case so that the twine will be tightly 35 held. In case the needle operating lever 61 is disposed in intermediate position, the lug 96 on the edge of the disk 83 will engage said lever and move the same to the position seen in Fig. 10, so that the needle will be 40 wholly disposed within the case and will not project through the opening 70 and across the slot 45. Thus, the possibility of the needle being broken or of its preventing the reverse movement of the mechanism by 45 engagement with the bag, is obviated. At the start of this reverse movement, the twine is withdrawn for a short distance along the front of the bag until it is caught and held by the plate 94 in the manner above explained, at which time the cutting edge 119 50 of the plate 118 will engage and sever the twine. It will be understood, of course, that there is sufficient slack in the twine so that it will not be pulled entirely from the eye of the needle in the reverse movement of the 55 sewing mechanism to its original position, the gear 47 will rotate freely upon the shaft 46, the pawls 51 moving idly over the respective 60 ratchets 50. It will thus be apparent that the gearing will not be actuated to continue the operation of the sewing mechanism.

After the bag or sack has thus been sewed, the crank 20 is actuated to project the angle 65 bar 15 outwardly and release the sack which

is now removed, together with the clamping or gripping device engaged upon the edges of the bag walls. This device can be readily detached by simply pressing the handle members 34 toward each other, as will be 70 clearly understood.

In Figs. 24 and 25, I have illustrated a spout or chute 127, through which the grain may be discharged from the grain receiving chamber of a threshing machine into the sack or bag. At the end of this chute, and upon the bottom wall thereof, a gate 128 is pivotally mounted intermediate of its ends, as at 129. This gate is formed with side plates or wings 130 which extend along the outer sides of the chute. When in its operative position, the bottom wall of the gate extends at a downward inclination with respect to the bottom wall of the chute and is provided at its lower end with a suitable 80 handle 131. The other end of said gate is connected by rods 132 to arms 134 on the opposite ends of a rock shaft 133 which extends transversely across the bottom wall of the chute at a point in spaced relation to the 85 gate. Coil springs 135 surround the rock shaft at opposite sides of the chute and are fixed at one of their ends to the walls of the chute and have their other ends operatively engaged with the respective crank arms 134. 90 To the rock shaft, a feed cut-off plate 136 is fixed and in one position is adapted to cut off the further gravity movement of the grain from said chute. The springs 135 normally act to rotate the rock shaft and move 100 the cut-off plate 136 to this position, the gate 130 being simultaneously moved through the medium of the rods 132 across the end of the chute, as seen in Fig. 25. To open the chute for the discharge of the grain, it is 105 only necessary to grasp the handle 131 and swing the gate 130 downwardly to the position seen in Fig. 24, where it will be noted that the ends of the rods 132 which are pivotally connected to the gate, are disposed 110 slightly above the gate pivot 129 so that the pressure exerted by the springs 135 will not return the gate to its normal position. As soon, however, as the gate is tilted upwardly to a sufficient distance to lower the ends of 115 the rods below the line of the pivot 129, the springs 135 will continue the closing movement of the gate and at the same time move the cut-off plate 136 to closed position. Thus, the further feed of the grain may be 120 very quickly cut off so as to eliminate to a large extent waste of the grain.

From the foregoing description, taken in connection with the accompanying drawings, it is believed that the construction, manner of operation and several advantages of my improved bag or sack sewing mechanism will be clearly and fully understood. The invention may be readily adapted and applied to the ordinary threshing machine, 125 130

or to combined harvesters and threshers of the modern type which thresh the grain in the field as it is harvested. The necessary manual operations may be easily performed 5 with a minimum of labor by a single attendant, and owing to the very compact arrangement of the several elements of the mechanism, it will occupy but relatively small space upon the machine. In view of the 10 very simple construction of the several parts of the mechanism, as above disclosed, it will be apparent that the device will be positive and reliable in its operation, durable in construction, and not liable to easily get out of 15 order.

While I have herein shown and described the preferred form, construction and relative arrangement of the various parts of the device, it is nevertheless to be understood 20 that the same are susceptible of considerable modification and I, therefore, reserve the privilege of adopting all such legitimate changes as may be fairly embodied within the spirit and scope of the invention as 25 claimed.

I claim:—

1. In a bag sewing machine, a shiftable case having a longitudinally extending slot to receive a bag, sewing mechanism mounted 30 within said case and including a reciprocating needle movable across said slot, means for actuating said mechanism in the movement of the case in one direction and means for retracting the needle within the case 35 when the case is moved in the opposite direction.

2. In a bag sewing machine, a horizontally shiftable case having a slot therein to receive a bag, manually operable means for shifting said case, sewing mechanism arranged within the case and including a needle movable across said slot, means for actuating the sewing mechanism in the movement of the case in one direction and 40 means for retracting said needle within the case and holding and severing the sewing twine when the case is moved in the opposite direction.

3. In a bag sewing machine, a horizontally shiftable case having a slot therein to receive a bag, manually operable means for shifting said case, sewing mechanism arranged within the case and including a needle movable across said slot, means for 45 actuating the sewing mechanism in the movement of the case in one direction, said means being inoperative in the movement of the case in a reverse direction, and means automatically operating at the start of such reverse movement to retract the needle and position the same entirely within the case.

4. In a bag sewing machine, a horizontally shiftable case having a slot therein to receive the closed end of a bag, sewing 55 mechanism mounted within said case and

including a reciprocating needle traversing said slot, means for actuating the sewing mechanism in the movement of said case in one direction, said actuating means being inoperative in the movement of the case in a reverse direction, means automatically operable to engage and hold the sewing twine in the movement of the case in the latter direction, and means carried by the case for severing the twine. 70

5. In a bag sewing machine, a horizontally shiftable case having a slot therein to receive the closed end of a bag, sewing mechanism within said case including a reciprocating needle to traverse said slot, a lever operatively connected to said needle, means for actuating the sewing mechanism in the movement of the case in one direction, said means being inoperative in the movement of the case in a reverse direction, 80 a disk rotatably mounted in the case and having teeth on its perimeter to engage the bag in the reverse movement of the case, said disk being further provided with means to coact with the lever and retract the needle from said slot, and means for actuating said mechanism in the movement of the case in one direction. 85

6. In a bag sewing machine, a horizontally shiftable case having a slot therein to receive the closed end of a bag, sewing mechanism within said case including a reciprocating needle to traverse said slot, a lever operatively connected to said needle, means for actuating the sewing mechanism in the movement of the case in one direction, said means being inoperative in the movement of the case in a reverse direction, a disk rotatably mounted in the case and having teeth on its perimeter to engage the bag in the reverse movement of the case, operating connections between said disk and said element to move the element in one direction in the operative shifting movement of the case and release the twine, said disk being 100 rotated in the reverse movement of the case to move said element into engagement with the twine and hold the latter against movement, and means carried by the case for severing the twine. 105

7. In a bag sewing machine, a horizontally shiftable case having a slot therein to receive the closed end of a bag, sewing mechanism within said case including a reciprocating needle to traverse said slot, a lever operatively connected to said needle, means for actuating the sewing mechanism in the movement of the case in one direction, said means being inoperative in the movement of the case in a reverse direction, a disk rotatably mounted in the case and having teeth on its perimeter to engage the bag in the reverse movement of the case, said disk being further provided with means to coact with the lever and retract the needle from 110 115 120 125 130

5 said slot, a twine engaging element mounted within the case, operating connections between said disk and said element to move the element in one direction in the operative shifting movement of the case and release the twine, said disk being rotated in the reverse movement of the case to move said element into engagement with the twine and hold the latter against movement, and means 10 carried by the case for severing the twine.

8. In a bag sewing machine, rectilinearly shiftable sewing mechanism, a twine holding and releasing means movable with said mechanism and including a part engageable 15 with the bag in the initial bodily operative movement of said mechanism to release the sewing twine and also engageable with the bag and operable thereby in the initial reverse movement of said mechanism to grip 20 and hold the twine, and means for subsequently severing the twine.

9. In a bag sewing machine, rectilinearly shiftable sewing mechanism, means for holding and releasing the sewing twine movable 25 with said mechanism and including a shiftable twine engaging member, a rotatable part, means operatively connecting said rotatable part to the shiftable member, said rotatable part engaging the bag in the initial 30 operative bodily movement of the sewing mechanism whereby it is rotated in one direction to shift said member and release the twine, said part being reversely rotated by engagement with the bag in the initial 35 reverse movement of said mechanism to shift said member into binding engagement with the twine, and means for subsequently severing the twine.

10. In a bag sewing machine, a rectilinearly shiftable case having a slot to receive the bag, sewing mechanism mounted within said case and including a pivotally mounted lever, a sewing needle on one end of said lever reciprocable across said slot in the pivotal movement of the lever, and means for actuating said lever.

11. In a bag sewing machine, a rectilinearly movable case having a slot to receive the bag, sewing mechanism mounted 50 within said case and including a lever fulcrumed intermediate of its ends, a sewing needle mounted on one end of the lever and reciprocable across said slot in the pivotal movement of the lever, and actuating means 55 operatively connected to the other end of said lever.

12. In a bag sewing machine, a rectilinearly movable case having a slot therein to receive the bag, sewing mechanism mounted 60 within said case and including a needle operatively mounted at one side of the slot and reciprocable across the same, stitch forming means mounted within the case at the opposite side of said slot, and means for 65 actuating the stitch forming means and the

needle in the movement of said mechanism in one direction.

13. In a bag sewing machine, a rectilinearly movable case having a slot therein to receive the bag, sewing mechanism mounted 70 in said case including a lever pivotally mounted in the case at one side of said slot, a sewing needle on one end of said lever reciprocable across the slot, stitch forming means mounted in the case at the opposite 75 side of said slot, and means for actuating said lever and the stitch forming means in the movement of the sewing mechanism in one direction.

14. In a bag sewing machine a reciprocable case, sewing mechanism within said case, means actuated by the movement of said case in one direction to release the sewing twine and actuate said sewing mechanism and means actuated by movement of 85 said case in the opposite direction for retracting said sewing mechanism entirely within said case and holding and severing the sewing twine.

15. In a bag sewing machine, rectilinearly shiftable sewing mechanism, means for actuating said sewing mechanism when moving in one direction and a twine holding and releasing means movable with said mechanism and adapted to release the sewing 95 twine when the sewing mechanism is being moved in the direction in which it is operated and to engage the twine and hold the same against movement when sewing mechanism is being moved in the opposite 100 direction.

16. In a bag sewing machine, rectilinearly shiftable sewing mechanism, means for actuating said sewing mechanism when moving in one direction, a twine holding and 105 releasing means movable with said mechanism and adapted to release the sewing twine when the sewing mechanism is being moved in the direction in which it is operated and to engage the twine and hold the 110 same against movement when sewing mechanism is being moved in the opposite direction, and means associated with said mechanism for severing said twine during the 115 movement of the sewing mechanism in the last named direction.

17. In a bag sewing machine a reciprocable case provided with a slot adapted to receive a bag, sewing mechanism mounted within said case and including a reciprocable needle movable transversely of said slot, means operated by the movement of said case in one direction for actuating said sewing mechanism, a member carried by said case and projecting into said slot for 120 engagement with the bag being sewed, means operated by the engagement of said member by the bag when the case is being moved in the aforesaid direction for releasing the 125 sewing twine and means operated by the 130

engagement of said member with the bag when the case is moved in the opposite direction for withdrawing said needle within said case and holding said sewing twine against movement.

18. In a bag sewing machine a reciprocable case provided with a slot adapted to receive a bag, sewing mechanism mounted within said case and including a reciprocable needle movable transversely of said slot, means operated by the movement of said case in one direction for actuating said sewing mechanism, a member carried by said case and projecting into said slot for en-
- 10

gagement with the bag being sewed, means 15 operated by the engagement of said member by the bag when the case is being moved in the aforesaid direction for releasing the sewing twine, means operated by the engagement of said member with the bag when 20 the case is moved in the opposite direction for withdrawing said needle within said case and holding said sewing twine against movement, and means carried by said case for severing the twine. 25

In testimony whereof I affix my signature.

JACOB EMIL SCHMANDT.
